UNITED STATES PATENT OFFICE.

LOUIS WOJIDKOW, OF NEW YORK, N. Y.

DESIGN FOR A STAND FOR CHAFING-DISHES.

SPECIFICATION forming part of Design No. 29,879, dated December 27, 1898.

Application filed October 20, 1897. Serial No. 655,853. Term of patent 3½ years.

To all whom it may concern:

Be it known that I, LOUIS WOJIDKOW, a citizen of the United States, residing at New York, (Brooklyn,) county of Kings, and State of New York, have invented and produced a new and original Design for Stands for Chafing-Dishes, of which the following is a specification, reference being had to the accompanying drawing, forming part thereof.

10 The drawing shows a perspective view of my design for a stand for chafing-dishes.

As shown in the drawing, the leading or material feature of my design consists of uprights or legs, which curve inwardly from the 15 top of the stand toward the intermediate portion thereof and below the intermediate portion are bent outwardly and inwardly into volutes.

10 The stand consists of a top ring A, a central lower bottom ring B, which is much smaller than the top ring, and uprights C, which are

formed at the top with volutes C', are bent abruptly inwardly toward the ring B, and are bent outwardly and inwardly into volutes C'', which extend below the ring B. Run around 25 the top ring A at one edge is a continuous rolling or open-loop scroll D, formed of connected node-shaped convolutions. A similar ornamental scroll D' is also run around the lower ring B.

Having described my invention, what I claim as new, and desire to secure by Letters Patent, is—

The design for a stand for a chafing-dish substantially as herein shown and described. 35

In testimony that I claim the foregoing as my invention I have signed my name in presence of two subscribing witnesses.

LOUIS WOJIDKOW.
